UNITED STATES PATENT OFFICE

CARL H. FRINK, OF CLAYTON, NEW YORK

SIDEWALK SNOWPLOW

Application filed October 18, 1929. Serial No. 400,527.

This invention relates to a snow plow attachment adapted to be mounted upon the front end of a motor tractor, truck or other self-propelled vehicle to be used more particularly for the removal of snow and ice from sidewalks and other relatively narrow pavements.

The main object is to provide a simple, compact and sturdy snow plow capable of being quickly and easily attached to and detached from the front end of any standard make of motor tractor or truck so that the moldboard will extend diagonally across and substantially equal distances beyond the opposite sides of the longitudinal center of the propelling vehicle.

Another object is to enable the plow attachment to be raised and lowered at will and to cause it to be automatically locked in any position of adjustment against downward movement under its own weight and at the same time to allow free vertical movement of the plow independently of its adjusting means.

A further object is to corrugate the front face of the moldboard vertically for the purpose of breaking up crust or ice which may be carried up across said face and thereby to reduce the resistance and liability of clogging of the snow and ice against the moldboard.

Another object is to yieldingly support the moldboard in such manner that it may be free to rock about a horizontal axis in case its lower edge encounters unyielding obstructions and to automatically return such moldboard to its operative position after passing such obstructions and thereby to reduce the liability of breaking or over-straining the plow attachment.

A further object is to provide the plow with an upwardly and forwardly extending shoe adapted to ride over curbs and other obstructions as when the machine is propelled from one side of the street to another.

Other objects and uses relating to specific parts of the plow and action will be brought out in the description.

In the drawings:—

Figure 1 is a side elevation of a motor trac-

tor and my improved plow attachment operably mounted thereon.

Figure 2 is an enlarged top plan of the detached plow attachment ready to be coupled to the front end of the motor vehicle as shown in Figure 1.

Figure 3 is a vertical sectional view taken in the plane of line 3—3, Figure 2.

Figure 4 is an enlarged detail sectional view taken in the plane of line 4—4, Figure 2.

Figure 5 is an enlarged transverse vertical sectional view taken in the plane of line 5—5, Figure 1.

Figure 6 is an enlarged horizontal sectional view taken in the plane of line 6—6, Figure 1.

Figure 7 is an enlarged transverse vertical sectional view of a portion of the moldboard showing the flat surfaces on the concave side thereof.

In order that the use of my improved snow plow attachment may be clearly understood I have shown it as mounted upon the front end of a relatively small motor tractor —A— of standard make so that the moldboard of the plow will be disposed in front of the tractor and diagonal to the longitudinal center thereof to extend substantially equal distances beyond the opposite sides of said longitudinal center and mainly between the outer sides of the tractor.

As illustrated, the skeleton frame of the plow comprises a horizontal bar or angle iron —1— bolted or otherwise secured to the under sides of the opposite lengthwise sills —a— of the tractor frame for receiving and supporting a pair of upright posts or angle irons —2— having their lower ends bolted or otherwise secured to the front face of the cross bar —1— equal distances from and at opposite sides of the longitudinal center of the motor tractor —A— to extend upwardly equal distances therefrom some distance above the hood of the tractor as shown more clearly in Figure 1, the upper ends of said posts being connected by an additional cross bar or angle iron —3— which is bolted or otherwise secured to said posts in a plane parallel with and some distance above the lower cross bar —1—.

A pair of lengthwise bars or angle irons ⁴ are bolted or otherwise secured to the upper cross bar ³ in parallel spaced relation equal distances at opposite sides of the longitudinal center of the tractor but in relatively close relation to extend forwardly and rearwardly beyond said cross bar ³ as shown more clearly in Figures 2 and 3.

The front ends of the lengthwise bars ⁴ are braced to the outer ends of the cross bar ³ by rearwardly diverging brace bars ⁵ having their front ends bolted or otherwise secured to the front ends of the bars ⁴ and their rear ends bolted or otherwise secured to the outer ends of the cross bar ³ as shown more clearly in Figure 2.

The front ends of the lengthwise bars ⁴ are also braced to the lower portions of the upright posts ² by downwardly and rearwardly extending brace bars ⁶ having their upper ends bolted or otherwise secured to the front ends of the bars ⁴ and their rear ends similarly secured to the opposite upright posts ² a relatively short distance above the lower cross bar ¹ as shown in Figures 1 and 3.

The intermediate portions of the upright posts ² may be additionally braced to the rear portion of the tractor frame ^{-a'} by brace bars ⁷ having their front ends bolted or otherwise secured to the corresponding posts ² and their rear ends extended along the outer sides of the hood of the tractor frame ^{-a'} as shown more clearly in Figures 1, 3 and 5.

The parts of the plow attachment thus far described constitute what may be termed a skeleton frame which, when secured to the under sides of the front ends of the tractor ⁴⁰ sills ^{-a}, is substantially rigid with the tractor frame and is adapted to carry the plow in a manner presently described.

As illustrated, this plow comprises a moldboard ⁸ which is concavo-convex in vertical cross section with its concave side facing forwardly and is supported in a manner to extend diagonally across and to equal distances at opposite sides of the longitudinal center of the tractor some distance beyond the ⁵⁰ front end thereof, said moldboard being provided with a multiplicity of flat surfaces arranged in sequence vertically from its lower to its upper edge as shown more clearly in Figure 7 to break its curved continuity for the purpose of breaking up the crust and ice which may be impinged thereagainst and thereby to reduce to a minimum the resistance to forward movement and liability of congestion of the snow and ice within the ⁶⁰ area of the moldboard when the plow is in operation.

A lengthwise reinforcing bar ⁹ preferably of angle iron is bolted or otherwise secured to the rear face of the moldboard ⁶⁵ adjacent its lower edge and parallel there-

with as shown more clearly in Figures 1 and 3.

A scraper blade ¹⁰ of hardened steel or equivalent material is bolted or otherwise secured to the front face of the moldboard near its lower edge to incline downwardly and forwardly therefrom so that its lower edge may be disposed in a substantially horizontal plane parallel with the lower edge of the moldboard, the same bolts being used for securing the scraper blade and reinforcing bar to said moldboard as shown in Figure 3.

The upper edge of the moldboard is deflected rearwardly and downwardly to form an angular reinforcing flange ¹¹ which cooperates with the bar ⁹ and blade ¹⁰ to stiffen the moldboard against deformation or against excessive springing action when in operation.

Additional upright reinforcing bars ¹² are bolted or otherwise secured to the rear face of the moldboard near the ends thereof and in longitudinally spaced parallel relation to extend from the upper face of the lower reinforcing bar ⁹ to the under side of the rearwardly projecting upper flange ¹¹, said reinforcing bars ¹² being made to conform to the curvature of the moldboard as shown more clearly in Figures 1 and 3.

The portions of the upright reinforcing bars ¹² between the longitudinal center of the moldboard ⁸ and horizontal reinforcing member ⁹ are provided with rearwardly turned flanges ^{12'}, preferably integral therewith, to form U-shaped clips for the reception of the front ends of a pair of thrust bars ¹³ which are hingedly connected to said clips by pivotal bolts ¹⁴ and are also pivotally connected at their rear ends by pivotal bolts ¹⁵ to the upright lower ends of the upright posts ².

A pair of additional thrust bars ¹⁶ are hingedly connected at their front ends to a U-shaped clip ¹⁷ on the rear face of the central portion of the moldboard ⁸ in about the same plane as the clips ^{12'}, the rear ends of said thrust bars ¹⁶ being pivotally connected to the bolts ¹⁵.

The outer thrust bars ¹³ are forwardly divergent from the pivotal bolts ¹⁵ to the clips ^{12'} to exert forward thrusts upon opposite ends of the moldboard when the machine is propelled forwardly.

The thrust bars ¹⁶ are rearwardly divergent from the clip ¹⁷ to the pivotal bolts ¹⁵ on the posts ² so that the forward ends are brought into close contact and embrace the U-shaped clip ¹⁷ which is located substantially midway between the clips ^{12'} and also substantially midway between the ends of the moldboard whereby the thrust bars ¹⁶ exert forward thrusts upon the central portion of the moldboard as

the machine is propelled forwardly, the points of engagement of the forwardly converging ends of the thrust bars —16— being located in substantial alinement with the longitudinal center of the machine.

The pivotal points of connection of the bars —13— and —16— with the moldboard, or rather with the upright reinforcing bars —12— and clip bolt —17—, are disposed in substantially the same horizontal plane below the horizontal center of the moldboard and still an appreciable distance above the bottom of said moldboard to allow a limited forward and rearward tilting movement of the moldboard about the axis of the pivotal members —14— and —17— particularly in case the scraper blade —10— should encounter more or less unyielding obstructions.

The pivotal bolts —15— for the rear ends of the thrust bars —13— and —16— are coaxial and at right angles to the center line of the machine and permit the moldboard and thrust bars to rock vertically about the axis thereof to lower and raise the moldboard to and from the pavement.

Under these conditions the moldboard will automatically lower itself by its own weight but is adapted to be raised by means of chains or cables —18— having their lower ends attached at —19— to the upright reinforcing bars —12— and their upper ends convergent upwardly and attached to a grab hook —20— which is mounted upon one arm of a bell crank lever —21—.

The angle of the bell crank lever is pivoted or fulcrumed at —22— to the front end of the upper horizontal bars —4— so that its opposite arms may diverge forwardly from the pivot, the front ends of the arms being connected by a brace bar —21'— for reinforcing purposes shown more clearly in Figures 1 and 3.

The pivotal bolt —22— is extended transversely across and through apertures in opposite sides of the bars —4— and has its intermediate portion enclosed by a spacing tube —23— between the bars —4— to assist in holding the latter in fixed spaced relation as shown more clearly in Figure 4.

The angular portion of the bell crank lever —21— is divided vertically and its opposite sides are spread apart to overlap upon the outer faces of the adjacent portions of the bars —4— and are apertured to receive the pivotal bolt —22— as shown in Figure 2, the front ends of the opposite sides of the bell crank lever being brought together and provided with a series of apertures —24— in spaced relation for receiving the grab hook —20— and permitting the latter to be adjusted to different positions relatively to the fulcrum or pivotal bolt —22— as may be required to vary the vertical movement of the moldboard of the plow by predetermined angular movement of the bell crank lever.

The front end of the upper arm of the bell crank lever —21— is provided with a pivoted clevice —25— for receiving a hook —26— of a tackle block —27— having a self-locking pawl —28—.

An additional tackle block —29— is provided with a hook —30— adapted to be attached to a clevice —31— which is pivoted at —32— to the rear end of the upper horizontal bars —4— as shown in Figures 1 and 2. These tackle blocks —27— and —29— are adapted to receive conventional sheaves around which is passed a cable —33— having one end attached to the tackle block —27— and its other end —33'— extended rearwardly within convenient reaching distance of the operator of the machine.

The rearwardly extending portion —33'— of the cable —33— is operably connected to the locking pawl —28— in such manner that when the cable is tightened for raising the plow through the medium of the bell crank lever —21— and chains —18— the locking pawl will be released but will automatically return to its locking position immediately upon release of the rearwardly extending portion —33'— of the cable.

As previously stated the moldboard —8— is pivotally attached by the members —14— and —17— to the thrust arms —13— and —16— to permit it to rock forwardly about the axis of those pivots in case the scraper blade —10— should encounter more or less rigid obstructions in its line of travel thereby reducing to a minimum, breakage or impairment of the plow incidental to such obstructions.

In order that the plow may be immediately restored to its operative position after passing over such obstructions I have provided a pair of coil springs —35— having their upper front ends connected to the upright bars —12— some distance above the pivotal bolts —14— and their lower rear ends connected by chains —36— to suitable clevices —37— on the intermediate portions of the outer thrust bars —13— some distance to the rear of the pivotal bolts —14— as shown more clearly in Figure 2.

These retracting springs —35— and their chains —36— extend downwardly and rearwardly in inclined planes from their points of attachment to the upright bars —12— to the thrust bars —13— so that in case the lower edge of the scraper blade should encounter more or less rigid obstacles sufficient to rock the moldboard about the axis of the pivotal bolts —14— and —17— such movement would be resisted by the springs —35— which would affect the instantaneous return of the moldboard to its operative position after passing such obstruction until limited by the tensioning of the chains —18—.

The opposite ends of the moldboard —9— are supported upon runners —38— and

—38'— of hardened steel or equivalent material having their front ends projecting beyond the front edge of the scraper blade —10— in upwardly inclined planes at —39— and their rear ends also bent upwardly at 5 —40— to enable the plow to ride along and upon the surface of the snow, ice or pavement, the upturned rear ends —40— being connected to the intermediate portions of 10 the upright reinforcing bars —12— by braces —41—, Figures 1 and 2.

The runner —38— for the advance end (in this instance the righthand end) of the diagonally disposed moldboard —9— extends 15 forwardly a greater distance beyond the front edge of the scraper blade —10— than the runner —38'— at the opposite end and has the front end of its upwardly inclined portion —39— connected by a U-shaped 20 brace —42— to the corresponding end of the upper flange —11— of the moldboard, said brace —42— having its apex at the front so that its opposite arms diverge rearwardly from said apex.

25 The lower arm of the brace —42— is therefore disposed in an upwardly and forwardly inclined plane and is bolted or otherwise secured to the underside of the extension —39— of the adjacent runner to form an additional rider bar —42'— adapted to ride over curbs and other obstructions when the plow is being transferred from one location to another, as for example, across the streets, it being understood that the plow is free to 30 move vertically by reason of the pivotal connection of its thrust links —13— and —16— with the lower ends of the upright posts —2—.

35 A substantially horizontal rub iron —43— is secured to the apex of the brace —42— and to the corresponding upright reinforcing bar —12— so as to substantially bisect the angle of the brace bar —42— and has its forward end curved inwardly at —43'— to reduce the 40 liability of the engagement of the front end of the brace bar and adjacent end of the plow with fences, bushes and other obstructions by simply deflecting those obstructions if possible or deflecting the plow laterally there- 45 from.

50 A landside plate —45— is secured along its upper edge to the guard rail or rub iron —43— to extend downwardly therefrom between the lower upwardly inclined portions 55 —39— and —42'— of the runner —38— and guard rail —42— respectively and adjacent end of the moldboard —9— for preventing side thrust of the plow particularly when passing through deep snow.

50 Operation

When the snow plow is mounted upon the front end of the tractor in the manner described the moldboard —9— and its thrust bars —13— and —16— will be adjusted

through the medium of the cable —33— and bell crank lever —21— to permit the scraper blade —10— on the lower edge of the moldboard to engage the sidewalk surface so that the latter may be cleaned from snow and ice by the forward movement of the tractor which movement is imparted to the plow through the medium of the thrust bars —13— and —16—.

70 In case the snow plow should encounter any serious obstructions in its path of movement the upturned ends of the runner —38— and —38'— and the lower part of the brace —42— will readily ride over those obstructions thereby elevating the plow which is permitted by the flexibility of the chains —18—.

75 Or in the event that the scraper blade should encounter more or less rigid obstructions sufficient to tilt the lower edge of the moldboard rearwardly and thereby elevate 80 the plow the latter would be immediately restored to its operative position by the springs —35— after passing such obstruction.

85 When desired the plow may be raised clear of the pavement by simply drawing rearwardly upon the portion —33'— of the cable thereby rocking the bell crank —21— rearwardly and upwardly and effecting a corresponding elevation of the plow through the medium of the chains —18—.

90 A separate vertical adjustment of the snow plow relatively to the pavement may be made by simply engaging one or the other of the links of the chain —18— in the grab hook —20—.

95 The front surface of the moldboard —9— serves to break up any crust which may be formed upon the snow and also any ice which may be dislodged from the pavement by the scraper blade —10— and greatly assists in 100 reducing resistance to the operation of the plow.

105 Otherwise the construction and operation of the machine has been described in such clear and exact terms as to enable anyone skilled in the art to make and use the same.

110 What I claim is:—

115 1. A snow plow attachment for motor tractors comprising a cross bar having means for securement to the front end of the tractor frame, upright posts secured to the cross bar in transversely spaced parallel relation, an additional cross bar secured to the upper ends of the posts, lengthwise bars secured to the upper cross bar to extend forwardly and rearwardly therefrom, braces between the front ends of the lengthwise bars and posts, a mold board extending diagonally across and to opposite sides of the longitudinal center of the tractor frame some distance in 120 front of the posts, thrust bars pivoted to the lower ends of said posts and diverging forwardly therefrom and having their front ends pivotally connected to the moldboard to permit the latter to swing forwardly and 125

rearwardly, spring connections between the moldboard and thrust bars, and means including a bell crank lever pivotally mounted upon the front end of the upper lengthwise bars for raising and lowering the moldboard.

2. A snow plow attachment for motor tractors comprising a frame having means for attachment to the tractor frame, thrust bars pivoted to the first named frame and diverging forwardly therefrom, additional thrust bars pivoted to the first named frame coaxial with the pivots of the first named thrust bars and converging forwardly from their pivots substantially midway between said first named thrust bars, a moldboard having co-axial pivotal connections with the front ends of said thrust bars to permit said moldboard to rock forwardly and rearwardly, and means supported upon the first named frame for raising and lowering the moldboard and adjacent portions of the thrust bars.

3. A snow plow attachment for motor tractors comprising a lower cross bar having means for securement to the tractor to extend across the longitudinal center near the front end thereof, posts having their lower ends rigidly secured to opposite ends of the cross bar and extended upwardly therefrom, an upper cross bar secured to the upper ends of the posts, lengthwise bars secured to the upper ends of the cross bars at opposite sides of a longitudinal center to extend forwardly and rearwardly therefrom, a moldboard extending diagonally across and to opposite sides of the longitudinal center of the tractor some distance in front of the lower cross bar, thrust bars pivoted to the lower ends of the posts and diverging forwardly therefrom and having their front ends pivotally connected to opposite ends of the moldboard, additional thrust bars pivotally connected to the posts and converging forwardly therefrom and pivotally connected to the intermediate portion of the moldboard, a bell crank lever pivotally connected at its angle to the front ends of said lengthwise bars and having its opposite arms diverging forwardly from its pivot, flexible connections between one of said arms and the moldboard, and a tackle connecting the other arm with the rear end of said lengthwise bars and operable at will for raising and lowering the moldboard.

4. A snow plow having a concavo-convex moldboard extending diagonally across the longitudinal center of the vehicle, and a shoe operably mounted on the moldboard to extend across the underside of and some distance forwardly beyond the front face of the moldboard and having its front end inclined upwardly and forwardly to guide the plow over obstructions when propelled forwardly, said shoe being located adjacent the end of the moldboard extending farthest forwardly, a brace connecting the front upturned

end of the shoe to the moldboard, a guard rail connecting the front portion of the brace to the moldboard, and a plate arranged edge-wise vertically between the guard rail and shoe to prevent side thrusts of the plow when passing through deep snow.

In witness whereof I have hereunto set my hand this 14th day of October, 1929.

CARL H. FRINK.
